UNITED STATES PATENT OFFICE.

JOHN HERSCHEL HARDCASTLE, OF BRISTOL, ENGLAND, ASSIGNOR TO BRITISH AND COLONIAL AEROPLANE COMPANY LIMITED, OF BRISTOL, ENGLAND.

PROJECTILE.

1,178,516.

Specification of Letters Patent. Patented Apr. 11, 1916.

Application filed December 30, 1913. Serial No. 809,573.

To all whom it may concern:

Be it known that I, JOHN HERSCHEL HARDCASTLE, a subject of the King of England, residing at Bristol, England, have invented certain new and useful Improvements in Projectiles, of which the following is a specification.

This invention has for its object to provide a new and improved projectile for rifled small-arms or ordnance which, when sufficiently rotated, offers less resistance to the air and has, under equal circumstances, a greater range than the projectiles at present in use. This projectile will be sufficiently rotated if it be given a spin in accordance with the tables already in common use for determining this point. It also, in flight, describes a flatter trajectory and requires less wind allowance.

In the accompanying drawings, forming a part of this specification, Figures 1, 2 and 3 are longitudinal sectional views of projectiles embodying my invention. Figs. 4, 5, 6, 7, 8 and 9 are views partly in side elevation and partly in longitudinal section illustrating other embodiments of the invention. Fig. 10 is a longitudinal sectional view showing another modification, and Figs. 11 and 12 are views partly in longitudinal section and partly in side elevation showing two more modifications.

Referring now to Figs. 1, 2, 3 and 4, the projectile 1 is so constructed that its guiding portion 2 (which is preferably cylindrical) occupies from one-eighth (see Fig. 1) to one-half (see Fig. 2) of the total length of the projectile, and is situated at the rear thereof. The head of the projectile is, in section, ogival, conical, paraboloid, or the like, or the head may be built up of conoidal sections. The curves of the head L are shown, in Figs. 1 to 4, as ogival, and are of a radius n of from 9 to 36 calibers c . The head, whatever its sectional contour, is from three to six calibers in length. In combining a guiding portion and point together to form a projectile so that the dimensions of the two parts lie within the respective limits hereinbefore stated, I do not intend that the dimensions chosen for the two parts should have no reference to the whole projectile resulting therefrom. For example, while the point portion may be as long as six calibers, if thereto a guide portion, whose length is half the total length of the pro-

jectile, be added, a projectile of twelve calibers length will result which is useless, and I make no claim to such a projectile. On the contrary, in applying the limits to each portion, while I wish the guiding portion to be made as short as is consistent with giving by its means satisfactory spin to the projectile from the rifling, I prefer not to employ a guiding portion greater than two calibers long and in no case are the proportions of the separate parts to be such that the over-all length of the projectile is greater than seven calibers. The tip of a projectile is preferably as sharp as possible. A projectile may also be constructed in accordance with the present invention with its head of a length as above described, but the said head, instead of being curved as shown in Figs. 1 to 4, may be in the form of one or more truncated cones having one cone-shaped piece at its tip. In the example illustrated in Fig. 5 there are shown three truncated cones 3, 4 and 5, and one complete cone 6, but I do not limit myself to this or any number of truncated cones, though, whatever their number, the longitudinal section of the series is substantially the same as though a continuous curve (such, for instance, as shown in dotted lines in Fig. 5) had been employed.

Another modification of the present invention consists in providing a projectile having a head of a length as above described, but wherein the contour of said head is either that of a cone, as shown in Fig. 6, or partially conical and partially ogival, as shown in Figs. 7 and 8, or it may be partially conical and have a tip the curves of which are convex to the longitudinal axis, as shown in Fig. 11, or may be partially ogival and have a tip the curves of which are convex to the longitudinal axis, as shown for example in Fig. 10.

By a still further modification of the present invention, a projectile may be constructed with a head which is partially conical and partially curved convex to its longitudinal axis, and with a cone 7 at the tip, as shown for example in Fig. 12.

A projectile constructed in accordance with any of the foregoing examples may have its guiding portion tapered for part of its length, as shown, for example, in Fig. 9, the said taper being employed for reducing barrel-friction or so adjusting weight as to

cause the center of gravity to lie at a pre-determined spot, or the like.

A projectile according to my invention is preferably composed of a material strong enough to resist any tendency on the part of the propelling gas to so compress the rear portion as to deform appreciably the curves of the head.

The term "guiding portion" used in the foregoing specification refers, when applied to projectiles for use with small-arms, to that portion thereof which bears rifling marks after having been fired; when applied to projectiles for use for ordnance, it refers to that portion thereof which extends from the driving band to where the effective point of the projectile begins.

A projectile constructed in accordance with this invention will be sufficiently rotated by rifling made in accordance with the tables at present commonly in use for determining this point.

What I claim as my invention and desire to secure by Letters Patent is:

25 1. In a pointed projectile the combination of a point-portion whose diameter throughout is less than the caliber of the rifle it is intended to be used in and whose length is between three times and six times 30 the said caliber and a portion to the rear of the said point of such length that the length of the point bears to the entire overall length of the bullet a value lying between 0.5 and 0.725, the parts being so chosen that 35 the said entire overall length does not exceed seven calibers.

2. In a pointed projectile the combination of a point-portion whose diameter throughout is less than the caliber of the rifle it is 40 intended to be used in and whose length

is between three times and four-and-a-half times the said caliber and a portion to the rear of the said point of such length that the length of the point bears to the entire overall length of the bullet a value lying 45 between 0.54 and 0.725, the parts being so chosen that the said entire length does not exceed seven calibers.

3. In a pointed projectile the combination of a point-portion whose diameter throughout is less than the caliber of the rifle it is intended to be used in and whose length is between three times and four times the said 55 caliber and a portion to the rear of the said point of such length that the length of the point bears to the entire overall length of the bullet a value lying between 0.06 and 0.725, the parts being so chosen that the said entire overall length does not exceed seven calibers. 60

4. In a pointed projectile the combination of a point-portion whose diameter throughout is less than the caliber of the rifle it is intended to be used in and whose length is between 3.5 times and 3.6 times the said 65 caliber and a portion to the rear of the said point of such length that the length of the point bears to the entire overall length of the bullet a value lying between 0.59 and 0.65, the parts being so chosen that the said 70 entire overall length does not exceed seven calibers.

In testimony whereof I have signed my name to this specification in the presence of two subscribing witnesses.

JOHN HERSCHEL HARDCASTLE.
